CLAIM

The ornamental design for a smart speaker, as shown and described herein.

DESCRIPTION

FIG. 1 is a front elevation view of a smart speaker showing the design;

FIG. 2 is a rear elevation view of the design;

FIG. 3 is a left-side elevation view of the design;

FIG. 4 is a right-side elevation view of the design;

FIG. 5 is a top plan view of the design;

FIG. 6 is a bottom plan view of the design;

FIG. 7 is a rear, right perspective view of the design;

FIG. 8 is a first reference view showing the smart speaker in a working state of the design; and,

(Continued)

FIG. 9 is a second reference view showing the smart speaker in another working state of the design.

The broken lines in the drawings depict portions of the smart speaker that form no part of the claimed design.
